METHOD OF FORMING SEVERABLE FLANGES FOR SLIP COVERS AND THE LIKE

Original Filed Dec. 12, 1934

UNITED STATES PATENT OFFICE

2,141,161

METHOD OF FORMING SEVERABLE FLANGES FOR SLIP COVERS AND THE LIKE

Leon E. La Bombard, Nashua, N. H., assignor to Oswego Falls Corporation, Fulton, N. Y., a corporation of New York

Original application December 12, 1934, Serial No. 757,164. Divided and this application October 30, 1936, Serial No. 108,455

4 Claims. (Cl. 93—39.1)

This invention relates to a method of forming slip covers for cylindrical containers of the type disclosed in my copending application, Ser. No. 757,164, filed December 12, 1934, of which this application is a division.

The invention consists in the method herein-after described and claimed.

In describing this invention, reference is had to the accompanying drawing in which like characters designate corresponding parts in all the views.

Figure 1 is a side elevation of a slip cover made in accordance with my method and showing a contiguous portion of the container, both being partly in section.

Figure 2 is a perspective view of a slip cover formed by the method herein described and illustrating the cover after the same has been removed from the container.

Figure 3 is a perspective view of the flange of the slip cover shown in Figure 2.

Figure 4 is a diagrammatic view illustrating the initial steps in carrying out the method herein described.

The slip cover, formed in accordance with the method herein described and claimed, is intended for use with fibrous cylindrical containers and is itself formed of fibrous material, such as paper, the construction of the cover being such that it is readily removable from the container by severing the depending flange of the cover which is effected by the novel construction of the same.

The object of this invention is a method by which a cover of such construction can be economically manufactured in large volumes. The flange of the slip cover is in the nature of a cylindrical tube and accordingly, the method herein referred to may be utilized to produce fibrous tubes of a structure which will permit ready severance of the tube, whereby the tube may be conveniently removed from any contents contained in the tube.

The slip cover shown in the illustrated embodiment of my invention comprises a discoidal portion 10 acting as a closure for the container and which is formed or provided with a depending cylindrical flange 11 which is of a diameter to slidably fit the upper end of the container barrel 12 in rather tight relation. The outer surface 50 of the flange 11 is provided with an incision 13 extending substantially through half the thickness of the flange, and the inner surface of the flange is provided with an incision 14 extending parallel to the incision 13 and in spaced apart 55 relationship thereto. The incision 14 extends

outwardly through substantially one-half the thickness of the flange. The incisions 13, 14, define overlapping portions 15, 16. If the container is filled with liquid, or semi-liquid products, the container barrel 12 has a tendency to swell or expand, in which instance the slip cover becomes tightly secured to the body of the container and is removed with appreciable difficulty.

In the construction above described, the slip cover may be readily removed from the body of the container by grasping the end 17 of the outer overlapping portion 15 and pulling it outwardly resulting in a severance of the flange 11 by separation of the overlapping portions 15, 16, the flange assuming the position shown in Figure 2.

This invention has to do particularly with the method of forming the overlapping portions 15, 16, of the flange, and more particularly in forming the incisions 13, 14. This method comprises generally, winding a tube having a plurality of overlapping layers with the layers arranged relatively to produce a spacing between the joints of the inner layer with those of the outer layer to provide an overlapping or severable portion of the flange.

Those skilled in the art of fabricating paper products are familiar with the commonly used method of winding paper tubes. These tubes are wound by feeding a plurality of strips of paper to a mandrel and wrapping the same about the mandrel in overlapping relationship. The strips are fed to the mandrel and wrapped about the same by continuously operating endless belts, the strips and belts being arranged at an angle relative to the axis of the mandrel, the angle determining the pitch of the wrapped layers of paper and the angle results from the width of the strips employed and the relative diameter of the mandrel, or the finished tube. Machines embodying this structure have been in common use over a long period of years.

I obtain the flange construction above described by the novel arrangement of the strips of paper fed to the mandrel of the tube winding machine. As here shown, the inner layer of the tube T is composed of two strips 20, 22, and the outer layer of a single strip 23 of width equal to the combined widths of the strips 20, 22. Normally, the inner and outer layers of the tube are wound so that the spiral joint of the outer layer overlaps the center of the inner layer and vice-versa, the spiral joint of the inner layer overlaps the middle of the outer layer. In other words, when the tube is cut through any plane, the outer seam

or joint is spaced 180° from the inner seam or joint 30, Figure 3.

To produce the flange shown in Figures 1 to 3, I divide the inner layer or strip into the two strips 20, 22. One of these strips, as strip 22 is of less width than the depth of the flange 11 of the slip cover. This results in the joint 24 between the strips 20, 22, being arranged slightly spaced apart or offset axially from the joint 25 formed by the convolutions or turns of the outer layer 23. The tube T thus wound is subsequently cut into sections, for example on lines 26, to form the flanges 11, in which instance the portion indicated at 25, Figure 4, becomes the end or point 17 of the outer overlapping portion 15 of the flange.

It will be understood by those skilled in the art that the width of the inner and outer layers and the relative width of the strips 20, 22, will depend upon the diameter and the length of the flange or tube to be produced. To carry out the invention, or to make a practical article, it is necessary that the lead or pitch of the joints 24, 25, be formed at an appreciable angle to the axis of the tube or flange. Otherwise, if the lead or pitch is slight, the incisions 13, 14, might extend completely around the flange or tube one or more times, depending upon the length of the tube or flange. For example, in the flange of the slip cover, as shown in Figures 1 and 3, the lead of the incisions 13, 14 and their relative spacing is such that the overlapping portions extend throughout 90° or less of the circumference of the flange, and because of the comparatively steep pitch or lead of the incisions, the overlapping portions 15, 16, may be readily and quickly severed. This results in a complete severance of the full width of the flange.

It will be evident that this steep pitch or lead with a comparatively narrow overlapping portion can not be obtained by winding the tube in the ordinary manner. In order to obtain the steep lead or pitch, it would be necessary to employ strips or layers of comparatively great width, with the result that the overlapping portion would be equal to one-half the width of the layers of the tube. By my method of winding, the steep lead or pitch can be readily obtained by employing inner and outer layers of appreciable width, and at the same time the overlapping portions 15, 16, may be varied at will by varying the width of one of the strips making up one of the layers, preferably by varying the strip as 22 of the inner layer, by which procedure the

width of the overlapping portions may be varied from very slight width to approximately one-half the width of the winding layers.

It will be observed that by my method the cost of winding the tube to obtain this particular result is not increased, nor is the production of the tube slowed up, and the utility of the completed product is readily apparent.

What I claim is:

1. The method of making slip covers for cylindrical containers comprising a discoidal portion and a depending flange portion, consisting in forming a tube of thin, flexible material having a plurality of layers, forming one of said layers of a plurality of strips with one of said strips not greater in width than the depth of the flange of the slip cover, severing the tube into sections, and securing a disk to one end of each section. 10

2. A method of making severable tubes consisting in winding a tube of thin, flexible material having a plurality of layers, forming one of said layers of a plurality of strips, one of said strips being of less width than the other, and the combined width of said strips being equal to the width of said other layer. 20

3. The method of making slip covers for cylindrical containers comprising a discoidal portion acting as a closure for the open end of the container, and a depending flange portion, said method consisting in winding a layer of thin, flexible material in tube form, winding a second layer superimposed on the first layer, said second layer being offset relative to the first layer axially of the tube a distance less than the depth of the flange of the slip cover, severing the tube into sections, and securing a disk to one end of each section. 30

4. The method of making slip covers for cylindrical containers comprising a discoidal portion and a depending flange, said method consisting of winding two strips of thin, flexible material of unequal width in parallel helical formation to constitute the inner layer of the tube, winding a third strip on said inner layer, said third strip being equal in width to the combined width of said first strips, and with each turn of said third strip completely overlapping each turn of the narrow strip and partially overlapping each turn of the wider strip, severing the completed tube into sections not greater in length 50 than the width of said wider strip, and securing a disk to one end of each section. 40
